OR D 13.839

DESIGN FOR A MANTEL-FACING.

Design No. 13,839, dated April 3, 1883.

UNITED STATES PATENT OFFICE.

ROBERT ROSSMAN, OF NEW YORK, N. Y.

DESIGN FOR A MANTEL-FACING.

SPECIFICATION forming part of Design No. 13,839, dated April 3, 1883.

Application filed July 11, 1882. Term of patent 7 years.

To all whom it may concern:

Be it known that I, ROBERT ROSSMAN, of the city, county, and State of New York, have invented a new and original Design for Mantel-Facings, of which the following is a full, clear, and exact description.

The nature of my design is fully represented in the accompanying photograph, to which reference is made.

10 The invention consists of a new and original design for mantel-facings composed of a floor, as hereinafter described, outlined in relief upon the corner, side, and top panels.

15 A in the illustration represents the top panel ornamented by two roses in relief in the center, with leaves and buds covering the remaining space. The corner panels, B, are ornamented in relief by a large rose with its stem and leaves. The side panels, C, are provided 20 with a garland of roses in relief, having their

stems and leaves at the bottom, a full-blown rose in the center, and the buds at the top. The flat surface tiles interposed between the relief tiles of the panels must be in keeping with the colors of the latter, so as to correspond thereto.

25 By employing this particular design a very artistic and unique ornamentation is obtained.

Having thus described my invention, I claim as new and desire to secure by Letters Patent— 30

The design in relief for mantel-facings, composed of side, top, and corner floral ornamentations, as hereinbefore described.

35 In testimony that I claim the foregoing as my invention I have signed it this 26th day of June, 1882.

ROBERT ROSSMAN.
